AUTOMATICALLY OPERATED RAILROAD GATE,
APPLICATION FILED JAN. 13, 1922.

Patented Nov. 28, 1922.

3 SHEETS—SHEET 3.

UNITED STATES PATENT OFFICE.

LAWRENCE KOKOVAI, OF DANTE, VIRGINIA.

AUTOMATICALLY-OPERATED RAILROAD GATE.

Application filed January 13, 1922. Serial No. 529,007.

To all whom it may concern:

Be it known that I, LAWRENCE KOKOVAI, a citizen of the United States, residing at Dante, in the county of Russell and State 5 of Virginia, have invented certain new and useful Improvements in Automatically-Operated Railroad Gates, of which the following is a specification.

This invention relates to an automatically 10 operated railroad gate and it has for an object to provide a novel device whereby a railroad gate will be operated by an approaching train, and further, to combine therewith a signal which will give warning 15 of the immediate closing of the gate.

For further comprehension of the invention, and of the objects and advantages thereof, reference will be had to the following description and accompanying drawings, and to the appended claims in which the various novel features of the invention 20 are more particularly set forth.

Fig. 1 of the drawings is a plan view of my improved automatically operated railroad gate.

Fig. 2 is a side view thereof.

Fig. 3 is a detail transverse section on the line 3—3 of Fig. 1.

Fig. 4 is a detail longitudinal section on the line 4—4 of Fig. 1.

Fig. 5 is a detail longitudinal section on the line 5—5 of Fig. 1.

Fig. 6 is a fragmentary plan view of the operating means, on a larger scale than Fig. 1.

In Figs. 1 and 2 of the drawings I have shown a section of a railroad track comprising rails 10 and ties 11. On each side of the track there is a gate comprising posts 40 12 having hinged thereto bars 13 normally held in raised position by springs 14. These bars 13 have attached thereto wires 15 which lead around suitable pulleys 16 to a drum 17. Leading rearwardly from drum 17, around pulleys 18, is a single pair of wires 19 which wind on a second drum 20 mounted on a bracket 21. By rotating drum 20 the gates are operated.

To rotate drum 20 a V-block 25 is fixed 50 on the end of a bar 26 slidable transversely of one of the track rails 10, the apex of block 25 being yieldingly engaged with the inner face of the rail tread. The opposite end of bar 26 is connected to a lever 27 ful-

crumed at one end to a bracket 27. The 55 other end of lever 27 connects to a transverse rack bar 28 slidable in a guide-bracket 29 and engaged by a pinion 30 loose on a shaft 31 extending longitudinally beside the rail. A spring pressed pawl 32 is mounted 60 on pinion 30 and engages a ratchet wheel 33 fixed on shaft 31. A tension spring 34 is connected to bar 28 and urges the same in a direction to keep the V-block 25 pressed against the rail. Shaft 31 is formed in two 65 sections united by ratchet faced clutch elements 36, one section being universally jointed as at 37. The clutch elements 36 are held yieldingly engaged with one another by means of a coiled expansion spring 38. 70

Loosely mounted on shaft 31 is a sprocket wheel 40 which is connected by a chain 41 with a second sprocket wheel 42 on an axially movable shaft 43 having a flattened forward portion 44. This shaft is guided 75 in suitable members 45 on the bracket 21. The forward end of this shaft has mounted thereon a spring pressed pawl 46 engaging a ratchet wheel 47 fixed on drum 20. Fixed in sprocket wheel 42 is a pin 42' engaging 80 in an elliptical groove 43' in shaft 43 so that rotary movement of the sprocket wheel moves this shaft longitudinally. Each time a train wheel engages the V-block 25 the shaft 43 is moved first forward, advancing 85 drum 20, and then backward, the pawl 46 disengaging from the ratchet wheel 47 in its rearmost position and resting on a stud 48 on the shaft.

As drum 20 is rotated step by step the 90 ropes are moved to likewise rotate drum 17 and lower the gate bars 13. To hold the bars 13 against upward movement one end of drum 17 has fixed thereto a ratchet wheel 50 engaged by a spring pressed pawl 51 95 carried on a disk 52 loose on the drum trunnion. In this disk 52 are closely spaced openings 53 into which a bolt 54, on one end of a bell crank lever 55, engages. To the other end of lever 55 is connected one end 100 of a cable 56 whose opposite end connects to a bell crank lever 56' operated by a V-block 57 on a sliding bar 58 when the train has passed the crossing it engages V-block 57 and thus causes the bolt 54 to 105 be retracted, leaving drum 17 free to rotate in a reverse direction under the influence of springs 14. A second rope 59 leads from

bell crank 55 back to a lever 60 passing between a pair of pins 61 carried by levers 27 so that upon lever 27 being operated when another train approaches the road the bolt 5 54 will be reset.

The signal device comprises an arm 65 pivoted on an offset 66 from a post 67 and having formed thereon an angular finger 68 connected by a link 69 with a bell crank 10 70 mounted in post 67. Extending longitudinally of the track is a shaft 71 having a crank element 72 connected by a link 73 with the bell crank 70.

Located at any suitable distance in advance of the V-block 25 is a second V-block 75 mounted on a bar 76 connected to an arm 77 pivoted at one end as at 78 and engaged with a rack bar 79 slidable in a guide member 80 similar to the member 29. This rack bar 79 having operative connection with the shaft 71 by means identical with that shown in Fig. 3. As the wheels of the train successively engage the V-block 75 the signal arm 65 will be oscillated, giving warning of 20 25 the approach of the train and the immediate closing of the gate. Reverse movement of shaft 71 is prevented by a ratchet and pawl device 85.

To close the gates by hand a shaft 86 is 30 provided with a crank handle 87 and is connected by gears 88 with a second shaft 89, parallel to shaft 31. Shaft 89 is connected by a sprocket chain 90, looped over suitable sprocket wheels with shaft 31, one of these 35 sprocket wheels having a ratchet and pawl connection with its shaft, similar to the connection of gear 30 with shaft 31.

Having thus described my invention what I claim as new and desire to protect by 40 Letters Patent of the United States is as follows:

1. In combination with a railroad track, pairs of hinged gate bars, a drum, ropes leading from said bars to said drum, a disk 45 loose on the drum trunnion, a ratchet wheel fixed on the drum, a pawl on the disk engaging the ratchet wheel, a locking bolt engaging said disk, means adapted to be operated by a train after passing the gate bars to retract said bolt, and means for rotating said drum step by step.

2. In combination with a railroad track, pairs of hinged gate bars, a drum, ropes leading from said bars to said drum, a disk 55 loose on the drum trunnion, a ratchet wheel fixed on the drum, a pawl on the disk engaging the ratchet wheel, a locking bolt engaging said disk, means adapted to be operated by a train after passing the gate bars 60 to retract said bolt, and means for rotating said drum step by step, said last means comprising a second drum, ropes connecting the two drums, and a movable train operated device adjacent a track rail and operatively connected to said second drum.

3. In combination with a railroad track, pairs of hinged gate bars, a drum, ropes leading from said bars to said drum, a disk loose on the drum trunnion, a ratchet wheel fixed on the drum, a pawl on the disk engaging the ratchet wheel, a locking bolt engaging said disk, means adapted to be operated by a train after passing the gate bars to retract said bolt, and means for rotating said drum step by step, said last means comprising a second drum, ropes connecting the two drums, and a movable train operated device adjacent a track rail and operatively connected to said drum, the operative connection between said train operated device and drum including a ratchet wheel 70 75 80 85 90 95 100 105 110 115 120 125 130 fixed to said drum, an axially movable shaft, and a pawl on said shaft adapted to move into and out of engagement with said ratchet wheel.

4. In combination with a railroad track, pairs of hinged gate bars, a drum, ropes leading from said bars to said drum, a disk loose on the drum trunnion, a ratchet wheel fixed on the drum, a pawl on the disk engaging the ratchet wheel, a locking bolt engaging said disk, means adapted to be operated by a train after passing the gate bars to retract said bolt, and means for rotating said drum step by step, and means adapted to be actuated by a train for releasing said bolt.

5. In combination with a railroad track, pairs of hinged gate bars, a drum, ropes leading from said bars to said drum, a disk loose on the drum trunnion, a ratchet wheel fixed on the drum, a pawl on the disk engaging the ratchet wheel, a locking bolt engaging said disk, means adapted to be operated by a train after passing the gate bars to retract said bolt, and means for rotating said drum step by step, and means adapted to be actuated by a train for releasing said bolt, said last means comprising a lever on which said bolt is mounted, an element adapted to be operated by a train, and a cable connecting said element and lever.

6. In combination with a railroad track, pairs of hinged gate bars, a drum, ropes leading from said bars to said drum, a disk loose on the drum trunnion, a ratchet wheel fixed on the drum, a pawl on the disk engaging the ratchet wheel, a locking bolt engaging said disk, means adapted to be operated by a train after passing the gate bars to retract said bolt, and means for rotating said drum step by step, said last means comprising a second drum, ropes connecting the two drums, and a movable train operated device adjacent a track rail and operatively connected to said second drum, the operative connection between said train operated device and drum including a slidable bar on which said train operated device is mounted, a spring engaging said bar and

pressing said train operated device against shaft carrying a pawl adapted to engage said the rail, a lever arm to which said bar is ratchet wheel, and a sprocket wheel thread-connected, a rack-bar connected to said levered on said last shaft and operatively connected to said first shaft.

5 shaft with which said pinion has a ratchet and pawl connection, a ratchet wheel fixed to said drum, a longitudinally movable
